INVENTOR:

Albert Abbe Griswold

By Chas. H. Luther

ATTORNEY:

UNITED STATES PATENT OFFICE.

ALBERT ABBE GRISWOLD, OF PROVIDENCE, RHODE ISLAND, ASSIGNOR OF ONE-HALF
TO JOHN FRANCIS CHEVALIER, OF BROOKLINE, MASSACHUSETTS.

FLEXIBLE UNDREAVE.

1,321,624.

Specification of Letters Patent. Patented Nov. 11, 1919.

Application filed August 2, 1919. Serial No. 314,976.

To all whom it may concern:

Be it known that I, ALBERT ABBE GRISWOLD, a citizen of the United States, residing at Providence, in the county of Providence and State of Rhode Island, have invented a new and useful Improvement in Flexible Undereaves, of which the following is a specification.

My invention has reference to an improvement in flexible shingles and more particularly to an improvement in a flexible under-eave now used in connection with the flexible shingles, as shown in my United States Patent No. 1,274,410, granted to me August 6, 15 1918.

In shingling a roof with flexible shingles laid diagonally, I find that the roof is greatly improved in construction and appearance and the operation of laying the shingles 20 greatly facilitated by the use of my improved under-eaves, which lay on the roof at the edge of the eaves and forms the first course in shingling the roof. Heretofore the shingles had to be cut off by hand or 25 bent under to form this first or eave course, which hand work requires skill, time, labor and extra expense.

The object of my invention is to provide a flexible under-eave for use in connection 30 with flexible shingles in shingling a roof with shingles laid diagonally, whereby the shingling of the roof is expedited and a more perfect roof of its kind constructed than has heretofore been done.

35 My invention consists in the peculiar and novel construction of a flexible under-eave, said flexible under-eave having details of construction, as will be more fully set forth hereinafter and claimed.

40 Figure 1 is a plan view of a portion of a flexible shingled roof, with the shingles laid diagonally and showing the same provided with my improved flexible under-eaves.

Fig. 2 is a plan view of my improved 45 flexible under-eave.

Fig. 3 is an end view of the under-eave, and

Fig. 4 is a plan view of the under-eave in the blank form.

50 In the drawings 5 indicates the sheathing of a roof, 6.6 the flexible shingles and 7.7 my improved flexible under-eaves. The roof sheathing 5 may also represent the sheathing on the outer walls of a building.

55 The flexible shingles 6.6 are constructed

as shown in my previous patent, of a flexible material and have a bent under corner flap 8 in which is a wire having outwardly extending side ends 9.9 which go under the angular lower edges 10.10 of shingles previously laid, to hold down the lower end of the shingle.

The flexible under-eaves 7.7 are formed preferably of the same flexible material as the shingles 6.6. Each under-eave 7 is preferably rectangular in shape, the same width as a shingle 6, and half the height of a shingle 6. The under-eave 7 is constructed to have a straight top 11, straight sides 12.12 and a straight eave edge 13. The eave edge 70 13 has the same finished surface as the outer surface of the under-eave, it is a rounded edge and is formed by bending the lower third of the material underneath forming an under flap 14 on the back or under side of 75 the under-eave, as shown in Fig. 3. Each lower corner of the under-eave is cut off at an angle forming an angular lower opening corner 15 which, when the sides of the under-eaves are together, answers the same 80 purpose as the lower angular edges 10.10 on the shingles 6.6. From each angular lower corner 15 a slit 16 extends in the eave edge 13, parallel with the eave edge 13, a predetermined distance, to facilitate the entrance of the wire side ends 9.9 on the shingles 6.6.

In shingling a roof or the like with my flexible shingles 6.6 laid diagonally and the under-eaves, the first course is formed by 90 laying my improved flexible under-eaves 7.7 on the roof with the eave-edges 13.13 at the eave edge of the roof, and secured at 17.17 by nails, as shown in Fig. 1. The shingles 6.6 are now laid by placing a 95 shingle over an under-eave in a position for the wire side ends 9.9 to go under the angular lower edges 15.15 of the under-eave. The shingle is then moved upward and the wire side ends 9.9 forced under the angular 100 lower edges of the under-eave thereby firmly securing the lower end of the shingle to two under-eaves previously nailed to the roof. The shingle is now nailed through its side corners to the roof and the course completed and the next course and other courses of shingles are laid and secured in the same way. The under-eaves 7.7 have the marks 105 18.18 to indicate where the under-eaves are to be nailed.

By the use of my improved flexible under-eaves the first course of shingles are laid more expeditiously, a material saving in time is obtained, and a more perfect shingled roof is constructed, at less cost, than has heretofore been done.

I do not wish to confine myself to the construction shown, as the same could be changed, such as eliminating the under flap 10 14 for cheapness, and the under-eave could 11 15 still be used for the same purpose.

Having thus described my invention I claim as new:—

1. A flexible under-eave formed of a fibrous material and having a bent under

flap forming a lower edge of two thicknesses and angular lower corners on the under-eave and extending across the lower corners of the bent under flap, for the purpose as described.

20

2. A flexible under-eave having a bent under flap forming a rounded lower edge of two thicknesses, angular lower corners on the under-eave extending across the bent under flap and merging into a slit at the lower 25 edge and parallel with the lower edge of the under-eave, for the purpose as described.

In testimony whereof, I have signed my name to this specification.

ALBERT ABBE GRISWOLD.
